THERMOELECTRIC DEVICE

Ernst Schwarz, Enfield, England

Application December 24, 1942, Serial No. 470,031
In Great Britain July 2, 1941

10 Claims. (Cl. 136—4)

This invention consists of improvements in or relating to thermo-electric devices. Such devices can be used for a variety of purposes as in pyrometers, in thermopiles, in thermo-converters (for converting alternating current to direct current) and so forth.

The objects of this invention are to improve the construction of thermo-electric devices, to increase the sturdiness (resistance to shock or vibration), to ensure a high sensitivity and a short time of lag, to minimise heat losses, to afford adaptability in the shape or size of the irradiated surface with efficiency in the use of said surface and to allow for wide variations in sensitivity and in resistance for any given thermo-electric power, and for any required conditions in the device as a whole.

According to this invention a thermo-electric device comprises in combination two conducting pillars each carrying at its outer end a small but sturdy body of a thermo-electric composition of high thermo-electric power fused or welded on to the supporting pillar so that said body can be mechanically worked (as by grinding), before the thermo-electric device is assembled. Also in accordance with the invention the other ends of the two conducting pillars may be mounted in a support and a conducting foil constituting or carrying the irradiated surface may be fixed to these bodies substantially normal to the pillars. The two thermo-electric elements may be in the form of cones, conical frustums, cylinders or prisms, fixed with their bases on the outer ends of the two parallel conducting pillars and the conducting foil may be fixed to the outer ends or tips of these bodies.

Each of the two elements may consist of a semi-conductor of high thermo-electric power and of low heat conductivity.

The thermo-electric elements are screened from irradiation by the conducting foil.

Two or more foils may be fixed side by side in one surface each with the two thermo-electric bodies and their conducting supports secured at the non-irradiated side.

One of the thermo-electric bodies may be thermo-electrically positive to the metal of the foil and the other body may be thermo-electrically negative to the foil so that their thermo-electric effects at the junctions with the foil are added.

The devices whether with single foil or with a plurality of foils may be secured in a hermetically-sealed container such as a glass vessel which may be evacuated.

The nature of the thermo-electric compositions

preferably used in the thermo-electric devices is set out in my United States patent application Serial No. 470,032 filed December 24, 1942, and broadly speaking each of such compositions includes one or more metals (preferably two or three metals such as silver, copper, lead and thallium) and elements of the sulphur group, namely sulphur, selenium and tellurium, and these substances are melted together to form the thermo-electric bodies of low heat conductivity.

The thermo-electric body may be fixed to the end of the pillar by fusion. Thereafter the thermo-electric body can be shaped as desired by mechanical working (particularly by grinding, say on an emery disc). When the thermo-electric body is fused or welded on to the supporting pillar and shaped as desired, each conducting pillar with its thermo-electric body is readily replaceable.

20 To fix the outer ends or tips of these special bodies to the inner face of the foil the foil is held against said ends or tips by resilient pressure (e. g. spring pressure) and is electrically welded by employing the discharge of an electric condenser through the junctions.

The time of lag is very low because there are no metals interposed at either of the hot junctions.

25 30 The nature of this invention and subsidiary features will be appreciated from the following description (by way of example) of practical embodiments.

In the accompanying drawing:

35 Figure 1 is a plan of one thermo-electric element, and

Figure 2 is a sectional elevation on the line 2—2 of Figure 1;

40 Figure 3 is an elevation, partly in section, of an element mounted in an evacuated glass bulb;

Figure 4 is an elevation showing an alternative form of single element;

45 Figure 5 is a detailed view illustrating the method of applying the thermo-electric body to its support;

Figure 6 is an elevation, partly in section, of several thermo-electric elements in series;

50 Figure 7 is a diagram showing the arrangement of thermo-electric elements in the case where irradiation may be received in two opposite directions;

Figure 8 is a plan view of a square irradiation surface indicating how the surface would be utilised in a thermo-electric device, and

Figure 9 is a diagram indicating the method

in which a cylindrical irradiation surface would be utilised in a thermo-electric device.

Referring to Figures 1, 2 and 3, for a single thermopile suitable for detecting and measuring radiation (e. g. infra-red rays, visible light, ultra-violet rays) the device as a whole comprises a glass container 12 with two leading-in wires 13, 14 fused into the base or foot and connected inside the container to two conducting rods 15, 16, say of nickel, which enter orifices in metal supports 20 and 21 held in a metal annulus 17. Projecting from the other (outer) side of the supports 20 and 21 are two parallel conducting pillars 18, 19, say of silver, the metal supports 20 or 21 making electric connection between the rods and pillars, or the rod 15 and pillar 18 may be integral and likewise the rod 16 and pillar 19 may be integral. The two supports 20 and 21 are separated from one another by a sheet of mica 22 and are also separated from the annulus 17 by sheets of mica 23 and 24. The conducting rods 15, 16 are secured in the supports 20 and 21 as shown in Figure 1 and the supports 20 and 21 are pressed together by an adjusting screw 25. At the outer ends of the pillars 18, 19 are secured the two thermoelectric bodies 26 and 27. One, for example the positive element, may be composed of silver, sulphur and selenium melted together and the other or negative element may be composed of copper, silver, tellurium, sulphur and selenium, and each body is in the form of a sturdy little cone with its base on the end of the pillar and its other end or tip outwards. The conducting foil 28 say of gold is secured on its inner face to the tips of the two cones 26, 27 and the outer face is blackened say with platinum black to form a receiving surface for irradiation. The glass container is exhausted to the degree of vacuum required and the surface of the glass may be covered or rendered opaque as at 29 but left clear at the necessary window or irradiation slit 30.

The heat from the highly-conducting receiver 28 goes to the tips of the thermo-electric bodies 26, 27 and as these have a very low heat conductivity, the heat loss is minimized although the sensitivity is high: further, as the container 12 is evacuated, conductivity through it is negligible.

The sensitivity and the electric resistance may be widely varied by varying the shape and area of the junctions between foil and thermo-electric elements.

Referring to Figure 4, the arrangement is almost the same as in Figures 1, 2 and 3, but in this case the thermo-electric bodies 31 and 32 are cylindrical. As shown, the block 33 is of insulating material such as ivory and the rods 15 and 16 are connected to the pillars 18 and 19 by metallic wedges 34.

Referring to Figure 5, a convenient method of securing the thermo-electric body, say 26, to its pillar 18 consists in applying a carbon ring 33 to the top of the pillar 18, placing a piece of the ready-made composition on the top of the pillar and subjecting the assembly to direct heat say from a blow-pipe flame so as to fuse the composition and weld it on to the top of the pillar 18, as indicated by the dot and dash lines. The carbon ring 33 prevents escape of the composition, or in other words retains the composition in its proper place. Thereafter the carbon ring 33 is removed and the thermo-electric body 26 is given the desired shape for example by grinding on a rotating energy disc or the like.

In cases where it is desired to use two or more

thermo-electric devices in series this invention provides for very convenient and thermo-electrically efficient arrangements. As above stated the foils are mounted side by side in one surface.

Referring to Figure 6, in the case of three square foils 28, they can be arranged in the same plane and in line with one another but spaced apart for insulation. Each foil has its two bodies 26, 27 at the back with their six supporting pillars 18, 19: the first and sixth pillars are electrically connected to the leading-in wires 13, 14, and positioned in supports 20 and 21 such as those shown in Figure 2, the second pillar is connected to the third and the fourth to the fifth by metal supports 36 so that the three devices are in series, it being understood that these supports are suitably insulated from each other in a manner similar to that shown in Figure 2. The whole exposed surface of the foils is utilised for receiving irradiation and the heat is transmitted to the tips only of the six bodies. In the same way a square surface as shown in Figure 8 may be divided up into say nine or sixteen square foils slightly spaced apart so that the whole receiver surface is utilised. The receiver surface may be cylindrical as shown in Figure 9 with the elements and pillars inside.

There are circumstances in which irradiation may be received in two opposite directions. In that case as shown in Figure 7 the alternate pairs of pillars 18, 19 may project from the metal supports 20, 36 and 21 in opposite directions and have the thermo-electric bodies and foils 28 fixed as above described. One special case where irradiation may be received in two opposite directions calls for a differential thermo-electric device which can detect or measure the difference between the radiation in the two opposite senses. In that case the devices on one side, instead of being connected in series with the devices on the other side, are connected in opposition so that if the thermo-electric effects on the two sides are the same, no voltage is generated, but if the radiation on the two sides differs, the voltage produced is a measure of the difference in radiation.

There are cases herein referred to as thermo-relays where a ray or beam may pass across a receiving surface and produce different thermo-electric effects in accordance with the position of the beam.

In such thermo-relays it is possible to use an irradiation surface in which are fixed two thermo-electric bodies which have the same sign in relation to the receiver. In such a thermo-relay 55 the metallic foil may be replaced by a foil made of one of the compositions above referred to such as the positive one, and in that case the two thermo-electric bodies mounted on the pillars are similar to one another and are made of the negative composition.

In any of the structures above described the foil 28 may be secured to the ends or tips of the thermo-electric bodies 27 or 32 by electric welding preferably employing the discharge of an electric condenser through the junctions. In this operation a suitable spring or other resilient member (not shown) may be employed to hold the foil in position against the tips prior to and during the welding operation.

This invention can be applied to the following uses:

1. In thermopiles for detecting and measuring radiation;
2. In thermo-converters for converting alternating to direct current;

3. In the transformation of radiation energy (say from the sun) into electric current;
4. For measuring degree of vacuum (as the sensitivity of the thermo-electric device increases as the gaseous pressure diminishes);
5. In electrical relays affected by radiation as in burglar alarms;
6. In pyrometers for measuring the total radiation from any body;
7. In differential or thermo-relays.

I claim:

1. A thermo-electric device comprising a pair of pillars of thermal and electrical conducting material, a base structure for supporting one end of each of said pillars with the other ends thereof adjacent but spaced from each other, a thermo-electric element secured to each of said pillars, each element forming an axial continuation of one of said pillars and having a base portion welded to said other end of said one of said pillars, said thermo-electric elements each being a small sturdy body of a thermo-electric composition having low heat conductivity, and a conducting foil element welded to both said bodies at their free ends.

2. A thermo-electric device comprising a pair of pillars of thermal and electrical conducting material, a base structure for supporting one end of each of said pillars with the other ends thereof adjacent but spaced from each other, a thermo-electric element secured to each of said pillars, each element forming an axial continuation of one of said pillars and having a base portion welded to said other end of said one of said pillars, said thermo-electric elements each being a small sturdy body of a thermo-electric composition having low heat conductivity, and a conducting foil element welded to both said bodies at their free ends, the ends of said bodies welded to said foil being smaller in diameter than said base portions.

3. A thermo-electric device comprising a pair of pillar members each having a metal body portion and a tip portion of a thermo-electric composition, said tip portion of each pillar forming an axial continuation of the body portion thereof and having a base portion welded to an end area of said body portion, said tip portions of said pillars being positioned adjacent each other, and an electrically conducting member joining the ends of said tip portions to form a thermopile.

4. A thermo-electric device comprising a pair of pillar members each having a metal body portion and a tip portion of a thermo-electric composition, said tip portion of each pillar forming an axial continuation of the body portion thereof and having a base portion welded to an end area of said body portion, said tip portions of

said pillars being positioned adjacent each other, the composition of one of said tip portions having positive thermo-electric characteristics and the composition of the other tip portion having negative thermo-electric characteristics, and a metal member joining the exposed ends of said tip portions to form a thermopile.

5. A thermo-electric device comprising a pair of pillar members each having a metal body portion and a tip portion of a thermo-electric composition, said tip portion of each pillar forming an axial continuation of the body portion thereof and having a base portion welded to an end area of said body portion, said tip portions of said pillars being positioned adjacent each other, and a metal foil united to the ends of said tip portions to form a thermopile and having its outer surface adapted for irradiation.

6. A thermo-electric device comprising a pair of pillar members each having a metal body portion and a tip portion of a thermo-electric composition, said tip portion of each pillar forming an axial continuation of the body portion thereof and having a base portion welded to an end area of said body portion, said tip portions of said pillars being positioned adjacent each other, and a metal foil welded to the outer ends of and joining said tip portions.

7. A thermo-electric device as defined in claim 4 in which the tip portions are conical and said metal member is a metal foil welded to and joining the apexes of said conical tip portions.

8. A thermo-electric device comprising a pair of pillar members each having a metal body portion and a tip portion of a thermo-electric composition, said tip portion of each pillar forming an axial continuation of the body portion thereof and having a base portion welded to an end area of said body portion, said tip portions of said pillars being positioned adjacent each other, the composition of said tip portions being substantially the same so as to have the same polarity, and an electrically conducting member having a thermo-electric composition of opposite polarity to that of said tip portions welded to and joining the ends of said tip portions to form a thermopile.

9. A thermo-electric device as defined in claim 5 in which the tip portions are screened from irradiation by the metal foil.

10. A thermo-electric device as defined in claim 6 which includes means for detachably supporting the ends of said pillar members opposite said tip portions to hold said pillar members in spaced parallel relation, and means to electrically insulate said last named ends from each other.

ERNST SCHWARZ.
